(57) **CLAIM**

I claim the ornamental design for a cooler table, as shown and described.

DESCRIPTION

FIG. 1 is a rear perspective view of the claimed design.

FIG. 2 is a rear elevation view thereof.

FIG. 3 is a front elevation view thereof.

FIG. 4 is a right-side view thereof.

FIG. 5 is a left-side view thereof.

FIG. 6 is a top plan view thereof.

FIG. 7 is a bottom plan view thereof.

FIG. 8 is a front perspective view of the claimed design with a bracket of the cooler table mounted to a cooler by a pair of fasteners of the cooler table and a table portion of the cooler table removed from the bracket; and,

FIG. 9 is a front perspective view of the claimed design with the bracket of the cooler table mounted to the cooler by the pair of fasteners of the cooler table and the table portion received by the bracket.

The invention pertains to an ornamental design for a cooler table. The cooler table is shown in FIGS. 1-9. In FIGS. 1-7, the cooler table is shown alone. In FIGS. 8 and 9, a bracket of the cooler table is shown attached to a cooler by a pair of fasteners of the cooler table. In FIG. 8, a table portion of the cooler table is shown removed from the bracket. In FIG. 9, the table portion of the cooler table is shown received by the bracket.

The solid lines represent the bounds of the claimed design, whereas those features shown in broken lines, such as the fasteners, shown in FIGS. 1-9, and the cooler, shown in FIGS. 8 and 9, form no part of the claimed design.
